UNITED STATES PATENT OFFICE.

CARL THEODOR LIEBERMANN, OF BERLIN, AND FRITZ GIESEL, OF BRUNSWICK, GERMANY.

PROCESS OF OBTAINING ECgonine.

SPECIFICATION forming part of Letters Patent No. 450,887, dated April 21, 1891.

Application filed September 18, 1888. Serial No. 285,716. (No specimens.) Patented in Germany August 14, 1888, No. 47,602.

To all whom it may concern:

Be it known that we, CARL THEODOR LIEBERMANN, a subject of the King of Prussia, residing at the city of Berlin, Prussia, Germany, and FRITZ GIESEL, a subject of the King of Prussia, residing at the city of Brunswick, Germany, have invented certain new and useful Improvements in Processes of Conversion of the Amorphous Alkaloids of Coca-Leaves into Eegonine and Benzoyl-Eegonine, (for which we have obtained Letters Patent in Germany, No. 47,602, dated August 14, 1888,) of which the following is a specification.

It is well known that the coca-leaves contain besides cocaine considerable quantities of amorphous alkaloids, which impair the physiological effect of cocaine and which have to be separated from the same or from the crude cocaine before it can be applied to therapeutic treatment. These amorphous alkaloids may be separated by solution and crystallizing out the cocaine, and they form the subject-matter of our invention.

The following method gives very satisfactory results: The coca-leaves are moistened with a twenty-per-cent. solution of soda and extracted by ether, which dissolves the cocaine and its amorphous alkaloids. By thoroughly shaking the ether with diluted muriatic acid the amorphous alkaloids are extracted and obtained in aqueous solution, from which they are precipitated by adding soda. The precipitate corresponds to the crude commercial cocaine in the market, and contains, according to the kind and quantity of the leaves employed, besides cocaine, varying quantities of amorphous alkaloids. By dissolving this precipitate—respectively the crude cocaine—heating it with a small quantity of alcohol, and permitting the solution to cool and stand for some time the cocaine crystallizes from the solution, while the amorphous alkaloids remain in solution and are obtained by the evaporation of the alcohol.

The method described, as well as other similar methods which were employed for producing cocaine from the coca-leaves or crude cocaine, furnish as a by-product the amorphous alkaloids referred to, which were not utilized, 50 constituted to some extent a loss or waste of cocaine. These amorphous alkaloids of co-

caine can, however, be utilized by our process, as by decomposing them eegonine can be readily obtained from said alkaloids, which eegonine can be converted into benzoyl-eegonine, 55 from which, by well-known methods, cocaine can be produced, so that by our process cocaine can be produced in a comparatively easy manner from by-products which heretofore had to go to waste. 60

In the preparation of eegonine from the amorphous alkaloids of the coca-leaves the amorphous alkaloids of cocaine readily undergo a reaction, by which they decompose into organic acids and eegonine, most of them with 65 a simultaneous formation of methyl-alcohol. This decomposition may be effected by acids or alkalies and alkaline earths and partially and insufficiently by superheated steam. We prefer to decompose the amorphous alkaloids 70 by boiling them with hydrochloric acid. The concentration or the quantity of this acid is of little importance; but we prefer to use hydrochloric acid of 1.1 to 1.2 specific gravity, which is used in excess. On the concentration 75 of the acid and the relative quantity of the same depends the time in which the reaction is complete, which takes usually from one to two hours or even a shorter time. The insoluble organic acids formed are, after cooling, filtered off, and the filtered liquor containing the hydrochlorate of eegonine is evaporated to dryness. The remaining salt, washed with a small quantity of alcohol, is nearly pure hydrochlorate of eegonine, from which the 85 free base is obtained by adding an alkali or alkali carbonate. The eegonine thus obtained may, if necessary, be purified by crystallization in alcohol. Eegonine is readily converted into benzoyl-eegonine, and for this purpose 90 either chloride of benzoyl or benzoic anhydride and dry eegonine or eegonine with a smaller quantity of water may be employed.

We herewith give an example of benzoylating eegonine; but we do not wish to confine 95 ourselves either to the use of benzoic anhydride only, as other substances—for instance, chloride of benzoyl—give the same result; nor to the exact quantities and details, for the reason that larger quantities of benzoic anhydride or the exclusion of water gives satisfactory results. 100

An aqueous solution of ecgonine (one molecule) saturated at boiling-heat is added to an equivalent quantity of benzoic anhydride, (one molecule.) To complete the reaction we heat 5 the mixture for a short time (about one-half to one hour) to the boiling-point. To remove the benzoic acid produced, the product of the reaction is, after cooling, repeatedly shaken or agitated with ether. The remaining aqueous 10 solution begins to solidify to a crystalline mass, either immediately after shaking or after standing for some time. The crystals are separated from the mother-liquor by means of a pump and washed with a small quantity of water. They consist of benzoyl-ecgonine, which 15 is identical with and has all its properties with the benzoyl-ecgonine heretofore known. The mother-liquor contains some ecgonine which has escaped the process of benzoylation. This 20 liquor may be used directly for other benzoylating operations, or the ecgonine may be regained from it by any known process. The benzoyl-ecgonine thus obtained is then converted into cocaine by any well-known method, and is thus obtained from its worthless 25 by-products contained in the coca-leaves.

Having thus described our invention, we claim as new and desire to secure by Letters Patent—

1. The process herein described of producing 30 ecgonine from the amorphous alkaloids contained in the coca-leaves or in crude cocaine, said process consisting in decomposing the amorphous alkaloids by a suitable medium into organic acids and ecgonine, separating the organic acids by filtration from the solution, evaporating the latter, and crystallizing the ecgonine from the residue by means of alcohol, substantially as set forth.

2. The process herein described of treating 40 the amorphous residues from the manufacture of cocaine, which consists in the decomposing said amorphous alkaloids by a suitable medium into organic acids and ecgonine, separating the ecgonine from its solution, and 45 converting it by treatment with benzoyl or benzoic anhydride into benzoyl-ecgonine, substantially as set forth.

In testimony whereof we have signed our names to this specification in the presence of 50 two subscribing witnesses.

CARL THEODOR LIEBERMANN.
FRITZ GIESEL.
